DIALKYL FORMAMIDES AS SELECTIVE SOLVENTS FOR REFINING MINERAL OILS

Virgil L. Hansley, Niagara Falls, N. Y., assignor to E. I. du Pont de Nemours & Company, Wilmington, Del., a corporation of Delaware

No Drawing. Application April 20, 1937,
Serial No. 137,928

15 Claims. (Cl. 196—13)

This invention relates to the separation of mixtures of hydrocarbons by selective solvent extraction and more particularly to the solvent refining of mineral oils.

5 It is now well known that a large proportion of the mineral oils and gasolines of today are complex mixtures of paraffinic and non-paraffinic hydrocarbons. It is frequently desirable to separate the non-paraffinic hydrocarbons from the 10 paraffinic hydrocarbons for various reasons. One of the main reasons is that the paraffinic hydrocarbons are in general more resistant to decomposition through heat and oxidation than the non-paraffinic hydrocarbons. Accordingly, the 15 oil containing the larger proportion of paraffinic constituents or, in other words, the relatively more paraffinic oils are more stable than the less paraffinic oils and hence are more desirable as lubricants and for other purposes.

20 Various methods have been proposed for separating the non-paraffinic from the paraffinic constituents of oils. One of the more common and oldest is by treatment with sulfuric acid which removes some of the non-paraffinic compounds from the oils. More recently it has been proposed to separate the non-paraffinic hydrocarbons by 25 means of selective solvent extraction.

An object of the present invention is to provide a method for separating a mixture of paraffinic and non-paraffinic hydrocarbons into portions, 30 one of which is relatively more paraffinic than the original mixture and the other relatively less paraffinic. Another object is the separation of relatively non-paraffinic bodies from mineral lubricating oils to produce lubricating oils of relatively high paraffinic character. A further object is the production of lubricating oils with improved viscosity-temperature curves from oils with poor viscosity-temperature curves. Still other objects 35 will appear hereinafter.

40 These objects may be accomplished in accordance with my invention which comprises treating mixtures of paraffinic and non-paraffinic hydrocarbons with an N-dialiphatic substituted formamide boiling below about 250° C. to remove 45 the non-paraffinic hydrocarbons by the selective action of the formamide. The dialiphatic formamides of my invention may be represented by the formula

50 wherein R and R' represent aliphatic hydrocarbon radicals. It will be understood that the term

“dialiphatic” as employed herein and in the claims will be restricted to hydrocarbon radicals and will include unsaturated and cyclic aliphatic hydrocarbon radicals as well as the saturated and open chain aliphatic hydrocarbon radicals.

5 The hydrocarbon mixture or oil is mixed with the formamide under such conditions that two layers are formed; one of which comprises the constituents which it is desired to extract from the oil dissolved in the bulk of the liquid solvent, while the other comprises the undissolved and relatively paraffinic oil in admixture with a relatively small amount of the solvent. Preferably, 10 my method comprises mixing the substituted formamide with the hydrocarbon mixture in approximately equal volumes and heating with agitation to a temperature at which the solvent and oil become substantially completely miscible. This solution is then cooled with agitation to a 15 temperature at least 20° C. below the temperature of complete miscibility. The resulting mixture is allowed to stand until it separates into two layers. The two layers are separated by separately withdrawing each layer. The dialiphatic formamide is recovered from each layer, preferably by 20 distillation. The residue from the layer containing the larger amount of solvent consists of a large proportion of non-paraffinic and undesirable constituents. The residue from the layer containing the smaller amount of solvent consists primarily 25 of the desirable paraffinic hydrocarbons.

30 In the examples given below, the selective removal of non-paraffinic constituents from a mineral oil has been measured by following the change in viscosity-gravity constant of the oil. This constant has been described by J. B. Hill and H. B. Coates in Industrial and Engineering Chemistry, Volume 20, page 641, et seq., in an article entitled “The Viscosity-Gravity Constant of Petroleum Lubricating Oils”. If a given crude 35 petroleum be distilled into successive fractions and the specific gravities and viscosities of the several fractions determined, it will be found that they conform to the general relationship:

$$G = a + \frac{1.0752 - a}{10} \log (V-38)$$

40 in which “G” is the specific gravity at 60° F., “V” is Saybolt Universal viscosity at 100° F., and “a” is the viscosity-gravity constant. These constants are lower for fractions of paraffinic crudes than are the constants for fractions of the naphthenic crudes. The viscosity-gravity constant is, therefore, an index of the paraffinity of an oil, and a decrease in the value of this constant for a 45

given fraction of lubricating oil indicates an increase in paraffin hydrocarbon content.

Example 1

- 5 A lubricating oil distillate (with the following characteristics: viscosity at 100° F., 566 sec. Saybolt Universal; specific gravity at 60° F./60° F., 0.927; viscosity-gravity constant, 0.872) was mixed with an equal volume of dimethyl formamide, heated with agitation to 115° C. at which temperature solvent and oil were miscible. The solution was cooled to 80° C., allowed to settle one-half hour, and the two layers withdrawn into separate containers. Dimethyl formamide was removed from both layers under reduced pressure. The top layer was found to contain 80% of the volume of the original oil and to have a viscosity-gravity constant of 0.848.
- 10 15 20

Example 2

- The lubricating oil distillate given in Example 1 was heated with agitation with twice its volume of dimethyl formamide to 100° C., cooled to 70° C., and allowed to settle one-half hour. The two layers which formed were then treated as in Example 1. The top layer was found to contain 67.5% of the original oil by volume and to have a viscosity-gravity constant of 0.845.

Example 3

- The distillate used in Example 1 was heated with an equal volume of diethyl formamide to 100° C. with agitation, cooled to 70° C. and allowed to settle one-half hour. After separation of the two layers and removal of solvent from each, an oil recovery of 76% was obtained from the top layer, this oil having a viscosity-gravity constant of 0.858.

- 40 45 50 55 60 65 70 75
- Dialiphatic formamides may be used with advantage in conjunction with other solvents which are known to possess selective solvent action in petroleum refining but which frequently have disadvantages of low separation temperatures and relatively poor yields of refined oil. Some of such other solvents are beta-beta'-dichloro-diethyl ether, nitrobenzene, cyclohexanol, methyl acetate, phenol, cresylic acids, cyclohexanone and aniline. Generally, the dialiphatic formamide should constitute from about 20% or more of such solvent mixture and preferably about 50% thereof. Used in conjunction with such solvents, dimethyl formamide materially raises the separation temperatures, avoiding the necessity of refrigeration, and improves the yield of refined oils. The following examples will illustrate these points:

Example 4

- 80 85 90 95 100
- A solvent was prepared by mixing one part of dimethyl formamide with one part of nitrobenzene. The lubricating oil distillate given in Example 1 was heated with an equal volume of this mixed solvent to 45° C., the temperature of complete miscibility. The solution was cooled to 20 C., settled one-half hour, and the separated layers treated as in the previous examples. From the top layer a yield of 70% of raffinate was obtained having a viscosity-gravity constant of 0.840. Nitrobenzene on the same stock under similar conditions required a separation temperature of 0° C. and yielded only 58% of raffinate of the same viscosity-gravity constant.

Example 5

- 75
- A solvent was prepared by mixing equal parts

of beta-beta'-dichlorodiethyl ether and dimethyl formamide. The lubricating oil distillate, given in Example 1 was treated with an equal volume of this mixed solvent in the same manner as in the previous examples, the temperature of miscibility being 80° C. and the separation temperature 25° C. A 76% yield of raffinate was obtained having a viscosity-gravity constant of 0.851. Under similar conditions, beta-beta'-dichlorodiethyl ether alone was miscible at 55° C. 10 and yielded 72% of raffinate having a viscosity-gravity constant of 0.856.

Example 6

15 20 25 30 35 40 45 50 55 60 65 70 75

Equal volumes of dimethyl formamide and cyclohexanol were mixed for use as a solvent. The lubricating oil distillate described in Example 1 was treated with an equal volume of the mixed solvent in the manner previously described, the temperature of complete miscibility being 75° C. Separation into two phases was accomplished at 25° C. The yield of raffinate from the top layer was 64% with a viscosity-gravity constant of 0.854. In attempting to use cyclohexanol alone on this stock, separation into two phases could not be accomplished even by chilling to 0° C.

While I have disclosed the use of dimethyl and diethyl formamides, in the above examples, other dialiphatic formamides with boiling points up to 250° C. may be employed in place thereof. Some of such other compounds which would be suitable are dipropyl formamide, di-isopropyl formamide, dibutyl formamide, di-isobutyl formamide, methyl ethyl formamide, 35 methyl propyl formamide, methyl isobutyl formamide, ethyl isopropyl formamide, ethyl butyl formamide, isopropyl isobutyl formamide, divinyl formamide, diallyl formamide, and similar compounds. However, the dialkyl formamides are 40 preferred and of these dimethyl formamide and diethyl formamide are the most satisfactory. Further, the dialiphatic formamides used for extraction need not be pure compounds but may be mixtures boiling between about 150° C. and 45 about 250° C.

50 55 60 65 70 75 80 85 90 95 100

The conditions of application of the solvent will vary with the nature of the oil. Highly naphthenic oils will, in general, require a lower temperature to effect separation than highly paraffinic oils. The temperatures employed will, in general, range from about 0° C. to about 200° C. At the higher temperatures, it may be necessary to employ pressure to prevent substantial vaporization of the solvent. The ratio of solvent to oil may be varied within rather wide limits and will depend largely upon the nature of the oil being treated, the amount of non-paraffinic constituents therein and the quality of the refined oil desired. In general, the ratio of solvent to oil will lie between 1 to 10 and 5 to 1 parts by volume.

85 90 95 100

The application of the dialiphatic formamides as selective solvents is not confined to lubricating oil distillates. They may be employed to refine other hydrocarbon or mineral oil fractions such as cracked naphthas, gasoline, or kerosene fractions, whose boiling ranges are sufficiently different from the solvent to permit separation of the solvent from the hydrocarbon mixture. Extraction treatment with the dialiphatic formamide may be applied to a raw distillate or to a partially refined product. Under certain conditions, for example in the case of oils with high sulfur content or poor sludging characteristics, 75

it may be desirable to supplement the extraction with the usual acid, alkali, doctor, or clay treatment applied either before or after the solvent extraction.

5 From the above disclosure, it will appear that I have provided new and improved selective solvents for refining petroleum oils and particularly for the production of high grade lubricating oil from mediocre crudes. The dialiphatic form- 10 amides possess high miscibility temperatures with oils thus permitting their utilization as extraction solvents over a wide temperature range. Further, the dialiphatic formamides may be employed in combination with other selective solvents having lower miscibility and extraction 15 temperatures to permit extraction at higher temperatures and with improved yields of refined oil.

While I have disclosed the preferred embodiments of my invention and the preferred modes of carrying the same into effect, it will be readily apparent to those skilled in the art that many variations and modifications may be made therein without departing from the spirit of my invention. Accordingly, the scope of my invention is to be limited solely by the appended claims construed as broadly as is permissible in view of the prior art.

I claim:

1. The method of treating a normally liquid hydrocarbon mixture containing relatively paraffinic and relatively non-paraffinic compounds which comprises extracting the hydrocarbon mixture with an N-dialiphatic formamide boiling below 250° C. to separate the relatively non-paraffinic compounds from the relatively paraffinic compounds.

2. The method of treating a normally liquid hydrocarbon mixture containing relatively paraffinic and relatively non-paraffinic compounds which comprises mixing an N-dialiphatic formamide boiling below 250° C. with the hydrocarbon mixture, causing the resulting mixture to separate into two layers and separating the layers, whereby the relatively non-paraffinic compounds are separated from the relatively paraffinic compounds.

3. The method of treating a normally liquid hydrocarbon mixture containing relatively paraffinic and relatively non-paraffinic compounds which comprises mixing with the hydrocarbon mixture an N-dialiphatic formamide boiling below 250° C., heating the resulting mixture to a temperature where the formamide becomes completely miscible with the hydrocarbon mixture, cooling the mixture to a temperature at least 20° C. below the temperature of complete miscibility and to where the mixture separates into two layers, separating the two layers, and removing the formamide from each layer, whereby the relatively non-paraffinic compounds are separated from the relatively paraffinic compounds.

4. The method of treating a normally liquid hydrocarbon mixture containing relatively paraffinic and relatively non-paraffinic compounds which comprises extracting the hydrocarbon mixture with N-dimethyl formamide to separate the relatively non-paraffinic compounds from the relatively paraffinic compounds.

5. The method of treating a normally liquid hydrocarbon mixture containing relatively paraffinic and relatively non-paraffinic compounds which comprises mixing N-dimethyl formamide with the hydrocarbon mixture, causing the resulting mixture to separate into two layers and separating the layers, whereby the relatively

non-paraffinic compounds are separated from the relatively paraffinic compounds.

6. The method of treating a normally liquid hydrocarbon mixture containing relatively paraffinic and relatively non-paraffinic compounds 5 which comprises mixing N-dimethyl formamide with the hydrocarbon mixture heating the resulting mixture to between about 100 and about 115° C., cooling the mixture to between about 70 to about 80° C. and causing the mixture to separate 10 into two layers, separating the two layers, and removing the dimethyl formamide from each layer.

7. The method of treating a normally liquid hydrocarbon mixture containing relatively paraffinic and relatively non-paraffinic compounds 15 which comprises extracting the hydrocarbon mixture with a solvent mixture comprising an N-dialkyl formamide boiling below 250° C. and a selective solvent having a substantially lower separation temperature, to separate the relatively 20 non-paraffinic compounds from the relatively paraffinic compounds.

8. The method of treating a normally liquid hydrocarbon mixture containing relatively paraffinic and relatively non-paraffinic compounds 25 which comprises extracting the hydrocarbon mixture with a solvent mixture comprising an N-dialkyl formamide boiling below 250° C. and nitrobenzene, to separate the relatively non-paraffinic compounds from the relatively paraffinic compounds.

9. The method of treating a normally liquid hydrocarbon mixture containing relatively paraffinic and relatively non-paraffinic compounds 35 which comprises extracting the hydrocarbon mixture with a solvent mixture comprising dimethyl formamide and a selective solvent having a substantially lower separation temperature, to separate the relatively non-paraffinic compounds from the relatively paraffinic compounds.

10. The method of treating a normally liquid hydrocarbon mixture containing relatively paraffinic and relatively non-paraffinic compounds which comprises extracting the hydrocarbon mixture with a solvent mixture comprising dimethyl formamide and beta-beta'-dichloroethyl ether to separate the relatively non-paraffinic compounds from the relatively paraffinic compounds.

11. The method of treating a normally liquid hydrocarbon mixture containing relatively paraffinic and relatively non-paraffinic compounds which comprises extracting the hydrocarbon mixture with a solvent mixture comprising dimethyl formamide and nitrobenzene, to separate 55 the relatively non-paraffinic compounds from the relatively paraffinic compounds.

12. The method of treating a normally liquid hydrocarbon mixture containing relatively paraffinic and relatively non-paraffinic compounds 60 which comprises mixing with the hydrocarbon mixture a solvent mixture comprising an N-dialkyl formamide boiling below 250° C. and a selective solvent having a substantially lower separation temperature, heating the resulting 65 mixture to a temperature where the solvent mixture becomes completely miscible with the hydrocarbon mixture, cooling the mixture to a temperature at least 20° C. below the temperature of complete miscibility and to where the mixture separates into two layers, separating the two layers and removing the solvent mixture from each layer, whereby the relatively non-paraffinic compounds are separated from the relatively paraffinic compounds.

13. The method of treating a normally liquid hydrocarbon mixture containing relatively paraffinic and relatively non-paraffinic compounds which comprises mixing with the hydrocarbon mixture a solvent mixture comprising an N-dialkyl formamide boiling below 250° C. and cyclohexanol, heating the resulting mixture to a temperature where the solvent mixture becomes completely miscible with the hydrocarbon mixture, cooling the mixture to a temperature at least 20° C. below the temperature of complete miscibility and to where the mixture separates into two layers, separating the two layers and removing the solvent mixture from each layer, whereby the relatively non-paraffinic compounds are separated from the relatively paraffinic compounds.

14. The method of treating a normally liquid hydrocarbon mixture containing relatively paraffinic and relatively non-paraffinic compounds which comprises mixing with the hydrocarbon

mixture a solvent mixture comprising N-dimethyl formamide and a selective solvent having a substantially lower separation temperature, heating the resulting mixture to a temperature where the solvent mixture becomes completely miscible with the hydrocarbon mixture, cooling the mixture to a temperature at least 20° C. below the temperature of complete miscibility and to where the mixture separates into two layers, separating the two layers and removing the solvent mixture from each layer, whereby the relatively non-paraffinic compounds are separated from the relatively paraffinic compounds.

15. The method of refining petroleum oil containing relatively paraffinic and relatively non-paraffinic compounds which comprises extracting the oil with an N-dialkyl formamide boiling below 250° C. to remove the relatively non-paraffinic compounds from the oil.

VIRGIL L. HANSLEY.
